UNITED STATES PATENT OFFICE.

CHARLES H. GAIL, OF CINCINNATI, OHIO, ASSIGNOR TO THE SHOTT MANUFACTURING COMPANY, OF CINCINNATI, OHIO, A CORPORATION OF OHIO.

BED-SPRING.

1,400,505.

Specification of Letters Patent. Patented Dec. 13, 1921.

Application filed June 21, 1920. Serial No. 390,312.

To all whom it may concern:

Be it known that I, CHARLES H. GAIL, a citizen of the United States, residing at Cincinnati, in the county of Hamilton and State 5 of Ohio, have invented certain new and useful Improvements in Bed-Springs, of which the following is a specification.

My invention concerns features of novelty and advantage in spring-cushion constructions, especially, but not necessarily restrictedly, in bed-springs embodying a plurality of upright spiral-springs which support the load.

One leading aim of the invention is the 15 provision of a structure of this kind in which the springs may be locally depressed by a load without substantial effect on the neighboring springs, whereby the occupancy of one side of the bed-spring by one person 20 will have little, if any, influence on the companion occupant of the other side of the spring. In other words, the bed-spring is so constructed as to eliminate any tendency for the occupants to roll toward the center 25 of the bed or the lighter weight occupant toward the one of heavier weight.

Further objects of the invention are the production of a bed-spring of this kind which possesses adequate resiliency, which is 30 noiseless, which is relatively simple in structure, which has a suitable transverse crown, and which is comparatively economical to manufacture.

In order that those skilled in this art 35 may have a full and complete understanding of the invention, both from structural and functional standpoints, a preferred and desirable embodiment of the same has been illustrated in the accompanying drawings 40 which should be considered in connection with the following detailed description of the structure and its mode of operation and throughout the several views of which like reference characters refer to the same parts.

45 In these drawings:

Figure 1 is a bottom plan view of the bed-spring;

Fig. 2 is a vertical cross-section through the bed-spring on an enlarged scale;

50 Fig. 3 is a fragmentary longitudinal section on line 3—3 of Fig. 2; and

Fig. 4 is a fragmentary enlarged cross-section at the center of the spring.

Referring to these drawings, it will be

seen that the bed-spring comprises a rectangular frame 10 including longitudinal side-bars 11, 11 of Z-shape in cross-section and end-bars 12, 12 of similar form in cross-section, which frame may be constructed in any approved manner. The middle portions 55 of the lower, inwardly-extended flanges 13 of such cross end-bars are connected together by an intermediate, longitudinal, angle-bar 14, having one flange horizontally disposed and resting on and fastened to the flanges 60 13, 13 and having its companion flange arranged vertically as is clearly indicated in Figs. 2 and 4. Fastened to the under faces of the inturned flanges 15 of the side-bars 11, 11 and to the bottom face of the horizontal flange of bar 14, are two spaced, hollow, transverse-bars 16 and 17 of any desired 65 shape in cross-section, whereby the frame as a whole is provided with six openings between the various intersecting or crossing 70 bars.

The lower flange 15 of each frame side-bar is connected to the upstanding flange of the intermediate, longitudinal angle-bar 14 at a higher level by a plurality of cross-wires 18, 80 18, end helical-springs 19, 20, and wire clips 21. Springs 19 extend through holes in the flanges 15, springs 20 being fastened to the intermediate bar by the clips which engage 85 holes in the upright flange of such latter bar.

These cross-wires, which are crimped at intervals as shown in Fig. 2, are associated at such spaced points with similarly-crimped, parallel, longitudinal wires 22, 90 which are omitted at the cross-bars 16 and 17. Thus, there are three sets of such lengthwise wires throughout the length of the frame. It will be appreciated, therefore, that this underlying, yielding supporting structure is divided into six sections, each being supported only crosswise of the frame, the wires 22 being wholly unconnected with the frame. By reason of this construction, the wires 22 may be depressed 100 without conflict or interference with the intermediate cross-bars, these interlaced wires at right-angles to one another constituting a flexible or pliable foundation or fabric on which the greater portion, but not all, of the 105 upright spiral-springs are mounted.

At each intersection or crossing of the supporting wires 18 and 22 an upright spiral-

spring 23 is mounted thereon in the usual manner, such springs in elevation having the shape shown in Figs. 2 and 3 resembling somewhat an hour-glass form. In addition, 5 a middle row 24 of such springs is mounted directly on the top edge of the central bar 14, being held from displacement by the associated clips 21. All around the frame and mounted thereon are a number of in- 10 wardly-extended brackets 25, 25 which support a plurality of shorter, upright, marginal, spiral-springs 26, held in place on such members by wires 27 interlocked therewith and extended through holes in such 15 brackets.

The usual rectangular border-wire 28 incloses such marginal springs which are secured to it by metal fasteners 29 of any suitable and convenient form, and the upper 20 or top coils or convolutions of all of the spiral-springs 23, 24 and 26 are connected together as shown by short, helical springs 30 of the construction set forth in my earlier United States Patent No. 1,263,548.

25 The spiral-springs 23 and 24 of the cross rows at their waists, or at about one-half of their height, are connected together by crimped or deformed, flat, metal-bands 31 which extend uninterruptedly from the 30 outermost spring 23 on one side of the structure to the corresponding spring on the other side. Such metal straps are associated with longitudinal wires 32 interlocked therewith at the springs and also locked with 35 such springs. Thus the upright disposition of the many springs is assured at all times, but it is to be noted that none of the elements 31 and 32 are connected to the frame.

It will be perceived that by reason of the 40 downward and opposite sloping of the sectional, underlying, supporting structure composed of the interlocked members 18 and 22 from the center-bar 14 to the frame side-bars, the top surface of the bed-spring 45 is given the proper transverse crown or arch to overcome sagging in the middle or central zone, and the avoidance of such objectionable depression is further fostered or aided by mounting the central or middle 50 row of springs 24 on the fixed or non-yielding support 14.

In addition, it will be observed that by supplying the border of the bed-spring with the shorter, upright spiral-springs supported directly on the brackets fastened to the frame, a desirable stiffer margin for the bed-spring is secured, whereby a person seated on the edge portion thereof does not unduly depress it.

60 To those skilled in this art it will be apparent that the invention is not limited and restricted to the precise and exact details of structure illustrated and described, but rather that these may be modified within

comparatively wide limits without departure 65 from the heart and substance of the invention and without the sacrifice of any of its substantial benefits and advantages. Stated somewhat differently, the invention is susceptible of a variety of embodiments of 70 which the one presented is merely a convenient example.

I claim:

1. In an appliance of the character described, the combination of a substantially-rigid frame having side and end bars and an intermediate longitudinal bar between and spaced away from said side-bars, a supporting-structure having independent sections on opposite sides of said intermediate bar and fastened thereto and to the corresponding side-bars of the frame, and upright spiral-springs mounted on said supporting-structure, substantially as described. 75

2. In an appliance of the character described, the combination of a substantially-rigid frame having side and end bars and an intermediate longitudinal bar between and spaced away from said side-bars, a supporting-structure having independent yielding sections on opposite sides of said intermediate bar and fastened thereto and to the corresponding side-bars of the frame, and upright spiral-springs mounted on said supporting-structure, substantially as de- 85

90

95

3. In an appliance of the character described, the combination of a substantially-rigid frame having side and end bars and an intermediate longitudinal bar between and spaced away from said side-bars, a supporting-structure having independent sections on opposite sides of said intermediate bar, helical springs fastening said sections to said intermediate bar and to the corresponding side-bars of the frame, said helical springs constituting the sole means securing said sections to said frame, and upright spiral-springs mounted on said supporting-structure, substantially as described. 100

105

110

4. In an appliance of the character described, the combination of a frame having longitudinal and end bars and a transverse-bar connecting the longitudinal bars together intermediate the end-bars of the frame, a supporting-structure comprising cross-members connected to the longitudinal elements of the frame and lengthwise members omitted at the transverse-bar to escape conflict therewith during depression, and a plurality of upright spiral-springs mounted on said supporting-structure, substantially as de- 115

120

scribed.

5. In an appliance of the character described, the combination of a frame having longitudinal and end bars and a transverse-bar connecting the longitudinal bars of the frame together intermediate the end-bars of

- the frame, a supporting-structure comprising cross-members connected by helical-springs to the longitudinal-bars of the frame and lengthwise members not directly connected with any part of the frame and omitted at the transverse bar to escape conflict therewith during depression, and a plurality of upright spiral-springs mounted on said supporting-structure, substantially as described.
6. In an appliance of the character described, the combination of a frame having side and end bars, a longitudinal-bar intermediate said side-bars, and a transverse-bar connected to said side-bars, between said end-bars, a supporting structure comprising cross-members connected to said side-bars and to said longitudinal bar and lengthwise members not connected directly with any portion of the frame and omitted in register with said transverse-bar, and a plurality of upright spiral-springs mounted on said supporting-structure, substantially as described.
7. In an appliance of the character described, the combination of a frame having side and ends bars, a longitudinal-bar intermediate said side-bars, and a transverse-bar between said end-bars, a supporting-structure comprising cross-members and lengthwise members, the latter not being directly connected with any portion of the frame and omitted in register with said transverse-bar, helical springs connecting said cross-members to said side-bars and to said longitudinal-bar, and a plurality of upright spiral-springs mounted on said supporting-structure, substantially as described.
8. In an appliance of the character described, the combination of a frame having side and end bars, a longitudinal-bar connected to said end-bars and located substantially midway between said side-bars, and a plurality of transverse-bars connected to said side-bars and longitudinal-bar between said end-bars, a supporting-structure comprising cross-members and associated lengthwise members, the latter not being directly connected with any portion of the frame and omitted in register with said transverse-bars, helical-springs connecting said cross-members to said longitudinal-bar and side-bars, and a plurality of upright spiral-springs mounted on said supporting-structure, substantially as described.
9. In an appliance of the character described, the combination of a frame having side and end bars and an intermediate longitudinal-bar between said side-bars, an underlying supporting-structure connected to said side-bars and to said intermediate-bar at a higher level than its attachment to said side-bars, and a plurality of upright spiral-springs mounted on said supporting-structure, substantially as described.
10. In an appliance of the character described, the combination of a frame having side and end bars and an intermediate longitudinal-bar between said side-bars, an underlying supporting-structure connected solely to said side-bars and to said intermediate-bar at a higher level than its attachment to said side-bars, and a plurality of upright spiral-springs mounted on said supporting-structure, substantially as described.
11. In an appliance of the character described, the combination of a frame having side and end bars and an intermediate longitudinal-bar between said side-bars, an underlying yielding supporting-structure connected solely to said side-bars and to said intermediate-bar at a higher level than its attachment to said side-bars, and a plurality of upright spiral-springs mounted on said supporting-structure, substantially as described.
12. In an appliance of the character described, the combination of a frame having side and end bars and an intermediate longitudinal-bar between said side-bars, an underlying supporting-structure comprising cross-members and associated lengthwise members, the latter not being directly connected with said frame, helical-springs connecting said cross-members to said side-bars and to said intermediate-bar at a higher level than their attachment to said side-bars, and a plurality of upright spiral-springs mounted on said supporting-structure, substantially as described.
13. In an appliance of the character described, the combination of a frame having side and end bars and a longitudinal-bar intermediate of said side bars, a sectional underlying supporting-structure having a part on each side of and connected to said longitudinal-bar and to the corresponding frame side-bar, a plurality of upright spiral springs mounted on said supporting-structure, and an intermediate row of upright spiral-springs mounted on said intermediate longitudinal-bar, substantially as described.
14. In an appliance of the character described, the combination of a frame having side and end bars and a longitudinal-bar intermediate of said side bars, a sectional yielding underlying supporting structure having a part on each side of and connected to said longitudinal-bar and to the corresponding frame side bar, a plurality of upright spiral-springs mounted on said supporting-structure, and an intermediate row of upright spiral-springs mounted on said intermediate longitudinal-bar, substantially as described.
15. In an appliance of the character described, the combination of a frame having side and end bars and a longitudinal-bar intermediate said side-bars, a sectional underlying supporting-structure having a part on

- each side of said longitudinal-bar, helical springs connecting each of said parts to said intermediate longitudinal-bar and to the corresponding frame side-bar, a plurality of upright spiral-springs mounted on said supporting-structure, and an intermediate row of upright spiral-springs mounted substantially-unyieldingly on said intermediate longitudinal-bar, substantially as described.
16. In an appliance of the character described, the combination of a frame having side and end bars and a longitudinal-bar intermediate said side-bars, a sectional yielding underlying supporting-structure having a part on each side of and connected to said longitudinal bar and to the corresponding frame side-bar, said attachment of the supporting-structure to said longitudinal-bar being at a higher level than the attachment to said side-bars, a plurality of upright spiral-springs mounted on said supporting-structure, and an intermediate row of upright spiral-springs mounted substantially-unyieldingly on said intermediate longitudinal-bar, substantially as described.
17. In an appliance of the character described, the combination of a frame having side and end bars and a longitudinal-bar intermediate said side-bars, a sectional yielding underlying supporting-structure having a part on each side of and connected to said longitudinal bar and to the corresponding frame side-bar, a plurality of upright spiral-springs mounted on said supporting-structure, an intermediate row of upright spiral-springs mounted on said intermediate longitudinal-bar, brackets mounted on said frame, and a plurality of border upright spiral-springs mounted on said brackets, substantially as described.
18. In an appliance of the character described, the combination of a frame having side and end bars and a longitudinal-bar intermediate said side-bars, a sectional yielding underlying supporting-structure having a part on each side of and connected to said longitudinal-bar and to the corresponding frame side-bar, said attachment of the supporting-structure to said longitudinal bar being at a higher level than the attachment to said side-bars, a plurality of upright spiral-springs mounted on said supporting-structure, an intermediate row of upright spiral-springs mounted on said intermediate longitudinal-bar, brackets mounted on said frame, and a plurality of border upright spiral-springs mounted on said brackets, substantially as described.
19. In an appliance of the character described, the combination of a frame having side and end bars and an intermediate longitudinal-bar between and spaced away from said side-bars, a plurality of rows of upright spiral-springs, the outer lengthwise rows being mounted unyieldingly on the frame side-bars, an intermediate longitudinal row being mounted unyieldingly on said intermediate-bar, and a yielding supporting-structure mounted on said frame carrying the remainder of the spiral-springs, substantially as described.
20. In an appliance of the character described, the combination of a frame having side and end bars and an intermediate longitudinal-bar between and spaced away from said side-bars, a plurality of longitudinal rows of upright spiral-springs, the outer lengthwise rows being mounted unyieldingly on the frame side-bars, an intermediate longitudinal row being mounted unyieldingly on said intermediate-bar, and a yielding supporting-structure mounted solely on the longitudinal members of said frame and carrying the remainder of the upright spiral-springs, substantially as described.
21. In an appliance of the character described, the combination of a frame having side and end bars and an intermediate longitudinal-bar between and spaced away from said side-bars, a plurality of upright spiral-springs arranged in longitudinal and transverse rows, the border springs all the way around the frame being mounted unyieldingly on said frame, an intermediate longitudinal row of said springs being mounted unyieldingly on said intermediate bar, and a yielding supporting-structure mounted solely on the longitudinal members of said frame and carrying the remainder of the upright spiral-springs, substantially as described.
22. In an appliance of the character described, the combination of a frame having side and end bars and an intermediate longitudinal-bar between said side-bars, a yielding supporting-structure having independent sections on opposite sides of and secured to said intermediate-bar and to the frame side-bars, the attachment of said sections to said intermediate-bar being at a higher level than their attachments to said side-bars, and a plurality of longitudinal rows of upright spiral-springs, the outer lengthwise rows being mounted unyieldingly on the frame side-bars, an intermediate lengthwise row being mounted unyieldingly on said intermediate-bar, the remainder of the spiral-springs being carried by said supporting-structure, substantially as described.
23. In an appliance of the character described, the combination of a plurality of upright spiral-springs, a rigid support for the side border springs of such group, a rigid support for an intermediate lengthwise row of such group of springs, and a yielding support for the springs between said border and intermediate rows, substantially as described.

24. In an appliance of the character described, the combination of a plurality of upright spiral-springs arranged in lengthwise rows and having their tops forming a 5 transversely crowned surface, the side border springs being of less length than the remainder of the springs, a rigid support for said shorter border springs, a rigid support for a substantially-central lengthwise row of said springs, and a yielding support for 10 the springs between said border and substantially-central rows, substantially as described.

CHARLES H. GAIL.
